US0D1098485S

(12) **United States Design Patent** (10) **Patent No.:** **US D1,098,485 S**
(45) **Date of Patent:** **** Oct. 14, 2025**

(54) **MEDICAL OR LABORATORY DIAGNOSIS DEVICE**

(71) Applicant: **Hunan Biometa Intelligent Manufacturing Technology Co., Ltd., Changsha (CN)**

(72) Inventors: **Lizhong Dai**, Hunan (CN); **Xun Zhong**, Hunan (CN); **Yaping Xie**, Hunan (CN)

(**) Term: **15 Years**

(21) Appl. No.: **35/522,601**

(22) Filed: **Oct. 11, 2023**

(80) **Hague Agreement Data**

Int. Filing Date: **Oct. 11, 2023**

Int. Reg. No.: **DM/232985**

Int. Reg. Date: **Oct. 11, 2023**

Int. Reg. Pub. Date: **Oct. 11, 2024**

(30) **Foreign Application Priority Data**

(57) **CLAIM**

The ornamental design for an medical or laboratory diagnosis device as shown and described.

DESCRIPTION

The patent or application file contains at least one drawing executed in color. Copies of this patent or patent application publication with color drawing(s) will be provided by the Office upon request and payment of the necessary fee.

1. Medical or laboratory diagnosis device

1.1 : Perspective

1.2 : Front

1.3 : Back

1.4 : Top

1.5 : Bottom

1.6 : Left

1.7 : Right

1.8 : Reference view

It is used for the extraction, amplification and analysis of molecules in biological samples, and it is suitable for clinical genetic testing laboratories, disease prevention and control centers, laboratories of scientific research institutes, laboratories of medical colleges and universities, etc.

**1 Claim, 8 Drawing Sheets
(8 of 8 Drawing Sheet(s) Filed in Color)**
